UNITED STATES PATENT OFFICE.

ANDREW G. SHEAK, OF BINGHAMTON, NEW YORK.

DRINKING-CUP.

972,932.

Specification of Letters Patent. Patented Oct. 18, 1910.

Application filed November 29, 1909. Serial No. 530,446.

To all whom it may concern:

Be it known that I, ANDREW G. SHEAK, a citizen of the United States, residing at Binghamton, in the county of Broome and State of New York, have invented a new and useful Drinking-Cup, of which the following is a specification.

This invention relates to drinking fountains and has for an object to produce a drinking fountain that is hygienic and may be installed in schools, public buildings, hospitals, and like places without necessarily placing it over a sink, bowl or other receptacle for catching the overflow water.

Another object is to provide a drinking fountain which will prevent a person when drinking from bringing his lips into contact with any part of the drinking cup.

A still further object is to provide the drinking cup with a truncated cone-shaped nozzle provided with a fine meshed wire or perforated top, over its inlet opening so that the jet of water issuing from the inlet opening will be directed above the surface of the water in the cup in a short, thick, steady column so that a person may readily quench his thirst without putting his lips down into the water in the cup.

A defect in many of the drinking cups now in use is that the drinker's lips may be brought into contact with some portion of the drinking cup. The cup is thus rendered unhygienic which feature prohibits the use of the drinking cups in schools and similar public places. This disadvantage I have overcome by placing an outer guard around the cup and so arranged that the person drinking must hold his mouth above the center of the cup where the water spouts up in a short, thick, steady column, in order to quench his thirst. In attempting to drink from the rim of the cup the drinker's chin is elevated by the outer guard so that his nose is brought into contact with the column of water issuing from the center of the drinking cup.

With the above advantages and other objects in view, which will appear as the description proceeds, my invention embraces certain novel details of construction and com-

bination of parts which will be hereinafter more fully described and claimed.

In the accompanying drawing forming part of this specification, — Figure 1 is a side elevation of a drinking fountain constructed in accordance with my invention with parts broken away. Fig. 2 is a transverse section through the drinking fountain showing the waste pipe in end elevation. Fig. 3 is a detail perspective view of the nozzle.

Referring now to the drawing, in which like characters of reference designate similar parts in the views shown, 1 designates the drinking cup provided at its bottom with a tubular nipple 2 provided with screw threads to engage the interior screw threads of a collar 3 carried upon the service pipe 4. The drinking cup is thus detachably secured to the service pipe and may be removed therefrom at any time in order to enable the fountain to be cleaned.

Arranged without the drinking cup 1 is an overflow bowl 5 provided with a tubular extension 6 to receive the service pipe 4. Arranged centrally in the bottom of the overflow bowl 5 is a tubular neck 7 which is connected in any desired manner to a waste pipe 8 through which the overflow from the drinking cup finds its way to a drain or suitable receptacle. The rim 9 of the overflow bowl is extended to a slight distance above the rim of the drinking cup and constitutes a guard for preventing a person when drinking from bringing his lips into contact with the edge of the drinking cup 1. It is evident that should a person attempt to insert his lips onto the edge of the drinking cup 1 the rim 9 of the overflow bowl will so elevate the drinker's chin that his nose will be brought directly over the center of the drinking cup 1 and into an upright column of water that issues from the inlet opening 10 of the nipple 2.

The overflow bowl may be dispensed with if desired when the cup is placed over a sink or other receptacle for catching the overflow water and a ring or its equivalent attached to the cup and so disposed that its rim will be spaced from and extend above the rim of the cup, as above described.

100

For reducing the pressure and spreading of the jet issuing from the inlet 10 and for producing a thick, steady column of water at the center of the cup 1, I have provided 5 a frusto-conical shaped nozzle 11, with a screened top. The base peripheral edge of nozzle 11 extends to form a circular flange 12, the outer edge of which engages and is rigidly secured in any preferred manner to 10 the inner walls of the drinking cup. The wide or intake end of the frusto-conical nozzle is thus spaced a slight distance from the throat of the inlet opening 10 so that a hemispherical chamber 13 is formed in the bottom 15 of the drinking cup which fills with water and operates to spread the incoming jet and reduces its pressure.

The converging walls of the nozzle direct the current of water, the pressure of which 20 has been reduced in the chamber 13, upward from the water in the drinking cup in a concentrated thick column, as shown in Fig. 1. The column of water rises a short distance above the surface of the water in the 25 cup, the relative height being regulated by a regulating valve 14 disposed in the service pipe. The fine meshed wire or perforated top of frusto-conical shaped nozzle 11 operates to further spread the incoming jet issuing 30 from the inlet opening 10. A steadier column is produced and the fountain can be operated with a much higher column of water without danger of the jet issuing from the opening 10, breaking through the body 35 of water in the cup in a small stream and spouting up to a great height. The fine meshed wire or perforated top of nozzle 11 permits the use of a much smaller opening in inlet 10 and the column of water can be 40 maintained the desired height with less water.

The advantage of being able to produce a comparatively high column of water is that a suitable column can be maintained under 45 varying pressure caused by drawing water in different parts of the building when the fountain is being used.

The conical cone-shaped screened nozzle that operates to spread the jet issuing from 50 the inlet 10, makes it practical to use a shallow cup. Since the size and force of a stream required to pass through a body of water and force up a spout to a given height is in proportion to the depth of the water 55 through which it passes, the advantage of a shallow cup is that less water is used to spout the water up to the required height. This affords economy in the use of water, often an important feature, especially when 60 it is desirable to have the water flowing continually. Further, the use of a shallow cup permits of a greater number of cups being used simultaneously on a single service pipe.

In order to discontinue the flow of water in the cup when desired, a stop cock 15 is 65 disposed in the service pipe adjacent to the regulating valve 14.

From the foregoing description, taken in connection with the accompanying drawing, it is thought that the construction and 70 operation of my invention will be readily understood without a more extended explanation, it being understood that various changes may be made in the form, proportion and minor details of construction without sacrificing any of the advantages or departing from the spirit of the invention. 75

What is claimed is:

1. A drinking fountain consisting of a cup having an inlet opening, a supply pipe 80 communicating with the inlet opening, and a nozzle having a tapered bore communicating with and of greater cross dimension than said inlet opening and operating to direct a short thick steady column of water 85 above the surface of water in the cup.

2. A drinking fountain consisting of a cup having an inlet opening, a supply pipe communicating with the inlet opening, a screened nozzle over said inlet opening having its bore communicating with and of greater diameter than the inlet opening, said bore being tapered from its intake to its discharge end whereby to direct a short thick steady column of water above the surface of 95 the water in the cup.

3. A drinking fountain consisting of a cup having an inlet opening; a supply pipe communicating with said inlet opening, a frusto-conical screened nozzle having its 100 base peripheral edges extended to engage the walls of the cup adjacent said opening, the bore of said nozzle communicating with and of greater diameter than said inlet opening whereby to direct the jet from the inlet 105 opening in a thick, steady column arising a short distance above the surface of the water in the cup.

4. A drinking fountain consisting of a cup having an inlet opening, a supply pipe 110 communicating with said inlet opening, a frusto-conical screened nozzle communicating with said inlet opening and having a peripheral flange to engage the walls of the cup whereby to space the intake end of the 115 nozzle from the throat of said opening, said nozzle operating to reduce the pressure and spread of the jet issuing from the inlet opening and direct said jet in a short, thick, steady column above the surface of the water 120 in the cup.

5. A drinking fountain consisting of a cup having an inlet opening, a frusto-conical nozzle over the inlet opening having a peripheral flange to engage the inner walls 125 of the drinking cup and coöperate therewith

to form a chamber to reduce the pressure and spread the jet from the inlet opening, and an overflow bowl without the cup and having its rim spaced from and extending 5 beyond the rim of the cup to prevent the lips from being inserted onto the edge of the cup.

6. A drinking fountain consisting of a cup having an inlet opening, a frusto-conical 10 screened nozzle over the inlet opening to reduce the pressure and spread the jet from the inlet opening, an outer guard spaced

from and extending beyond the rim of the cup to prevent the lips from being placed on the edge of the cup and compel drinking from the column of water issuing from the inlet opening of the cup. 15

In testimony that I claim the foregoing as my own, I have hereto affixed my signature in the presence of two witnesses.
